See application file for complete search history.

FIG. 2 is a second image thereof;

FIG. 3 is a third image thereof;

FIG. 4 is a fourth image thereof;

FIG. 5 is a front view of a second embodiment of a display screen or portion thereof with animated graphical user interface showing the claimed design;

FIG. 6 is a second image thereof;

FIG. 7 is a third image thereof; and,

FIG. 8 is a fourth image thereof.

The outermost broken lines in the figures show a display

screen or portion thereof, and form no part of the claimed

design.

The appearance of the animated image sequentially transitions between the images shown in FIGS. 1-4 and 5-8. The process or period in which one image transitions to another

forms no part of the claimed design.
